UNITED STATES PATENT OFFICE.

GUSTAV DAVERIO, OF OBERSTRASS, NEAR ZÜRICH, SWITZERLAND.

ROLLER-MILL FOR GRINDING GRAIN.

SPECIFICATION forming part of Letters Patent No. 235,517, dated December 14, 1880.

Application filed February 2, 1880. Patented in England October 8, 1877, and June 25, 1879.

To all whom it may concern:

Be it known that I, GUSTAV DAVERIO, of Oberstrass, near Zürich, Switzerland, have invented an Improved Crushing or Grinding 5 Mill for Grain and Other Substances; and I do hereby declare that the following description, taken in connection with the accompanying drawings, hereinafter referred to, forms a full and exact specification of the same, wherein I 10 have set forth the nature and principles of my said improvement, by which my invention may be distinguished from others of a similar class, together with such parts as I claim and desire to secure by Letters Patent—that is to say: 15 My invention relates to the construction of a crushing or grinding mill for which Letters Patent of the United States were granted to me on the 12th of February, 1878, No. 200,263. In such mill three rollers were arranged with 20 their axes in a nearly vertical line, and were surmounted by a feed-hopper with passages therefrom, so arranged that part of the grain or other substance to be operated on passed between the upper and middle rollers and part 25 passed between the middle and lower rollers.

The object of this invention is to provide novel means of regulating the squeeze of the rolls, to simultaneously adjust the feed at both sides of the mill, and to accurately adjust the 30 feed-openings independent of each other, all as will be fully hereinafter described.

On the accompanying drawings, Figure 1 is a part elevation and part vertical section of my said improved construction of mill. Fig. 35 2 shows an end elevation. Fig. 3 shows a section through the feed-hopper, and Fig. 4 shows a part sectional plan on line $x-x$, Fig. 2.

A' , A^2 , A^3 are respectively the upper, middle, and lower grinding-rollers, which may be either 40 smooth or grooved, the grain or other substance being fed separately between A' and A^2 and between A^2 and A^3 from the hopper M , in the manner described in my above-named patent.

The axis a^2 of the middle roller is carried in 45 fixed bearings, and is driven by a pulley, B , and strap or other convenient means, and imparts motion, by toothed gearing C , to the axes a' , a^3 of the upper and lower rollers, the gearing being so proportioned that the speed

of the upper and lower rollers is somewhat 50 less than that of the middle one.

The toothed wheels of the upper and lower rollers are, by preference, mortise-wheels.

The axes of the upper and lower rollers are mounted upon the short arms of bent levers 55 D' , D^2 , pivoted at d' , d^2 to the framing E , and having their long arms extending respectively downward and upward until they nearly meet at the center line of the middle roller, as shown. On the outer faces of such arms are adjusting- 60 pieces F' , F^2 , pivoted at f' , f^2 , which pieces have their one end extending to the ends of the lever-arms, and are both simultaneously acted upon by the eccentric G on an axis which can be turned by means of a lever, H , working in 65 a quadrant, H' . The other ends of the adjusting-pieces F' , F^2 have screws I passing through them and screwing into the levers D' , D^2 . The long arm of each lever D' , D^2 is furthermore 70 connected, by a pin, j , Fig. 4, to a spring-bolt, J , carried by the framing, which tends to draw these arms in the direction of the arrow, and consequently to make the short arms, together with the grinding-rollers A' and A^3 , to approach the roller A^2 . By this spring action the lever- 75 arms are brought with their adjusting-pieces F' , F^2 against the eccentric G as a stop, and thus it will be seen that, first, by turning the eccentric-stop G more or less round by means of the lever H the rollers A' , A^3 may be moved 80 nearer to or farther from the roller A^2 ; and, secondly, by adjusting the pieces F' , F^2 by means of the screws I the rollers A' , A^3 can each be independently adjusted accurately in 85 position relative to the roller A^2 , so as to obtain the exact degree of fineness required in the grinding process for each pair of grinding-rollers; also, assuming the rollers A' , A^3 to be set to their correct position when the eccentric-stop G is in the position shown in the drawings, with its smallest radius presented to the adjusting-pieces, then by turning it round by 90 means of its lever the rollers A' , A^3 may be quickly moved away from A^2 should any hard substance have passed between either of them, 95 so as to let it pass through, and thus prevent the clogging or injuring of the rollers. On then turning back the eccentric the rollers A'

A^3 will be at once drawn back into their original position by the spring-bolt J .

It will also be seen that by means of this spring-bolt the rollers $A' A^3$ are held in position with an elastic pressure capable of yielding somewhat, so as to prevent undue strain on the bearings.

The screws I are prevented from shifting after adjustment by means of spring-catches i taking into serrated rims on the screws.

The adjusting-pieces $F' F^2$ may either be pivoted to the faces of the levers $D' D^2$, as shown, or they may be sunk into recesses in the latter.

15 The eccentric-stop G is secured in whichever position it is set by means of a thumb-nut, h , holding the lever H in position in the quadrant H' .

The thrust of the bearings of the axes $a' a^3$ 20 is taken by anti-friction rollers $K' K^2$, carried in boxes $K^3 K^4$, which are hinged to the levers on one side, and are secured thereto by screws on the other side, so that by turning these screws the pressure of the rollers on the bearings can be regulated.

25 The bearings of a' and a^2 are lubricated by small rollers in cups $k' k^2$ below the bearings, containing the lubricant, while the bearings of a^3 are lubricated by the anti-friction rollers K^2 themselves, which dip into the lubricant contained in the box K^4 .

30 The two feed-apertures m of the feed-hopper M are provided with feed-rollers O , to which a slow rotary motion is imparted in the direction of the arrow, Fig. 3, by means of bevel-pinions L on a shaft, L' , carrying a worm-wheel, L^2 , in gear with a worm, P , on the axis a' of the upper roller.

35 For regulating the feed-openings of the hopper, slides Q carry screw-spindles R , screwing through screwed bushes R' , rotatable in brackets on the hopper M . These bushes have small bevel-pinions in gear with bevel-pinions S' on a spindle, S , passing right through the 40 hopper, and provided with hand-wheels S^2 , so that by turning the spindle S both slides are simultaneously moved up or down to regulate the feed-openings. For the more accurate adjustment of these openings the slides Q carry 45 plates Q' , turning on centers at q and having eccentric slots, through which pass screwed pins on subsidiary slides T , that are secured in the slots by thumb-nuts, so that by adjusting the slotted plates Q' the position of the 50 slides T can be adjusted accurately upon the slides Q , so as to insure a uniform delivery of the grain along the whole length of the feed-openings.

55 The devices for delivering the grain or other substance from the feed-openings to the grinding-rollers are the same as described in my former patent, and need not be further referred to.

60 I do not claim, broadly, two spring-impelled adjustable levers the ends of which serve as

bearings for the journals of upper and lower grinding or crushing rollers for adjusting the surfaces of said rollers in relation to each other, as such, broadly, is not new.

Having thus described the nature of my said 70 invention and in what manner the same is to be performed, I claim in respect of three-roller grinding or crushing mills—

1. In a grinding or crushing machine, the combination of the middle roll in fixed bearings, the upper and lower rolls geared with the middle roll, the vertical bell-crank levers pivoted at their angle, the short arms of said levers being provided with bearings, within which the journals of the upper and lower 80 rolls are respectively arranged and supported, the vertical adjusting-pieces $F' F^2$, connected to and parallel with the outer faces of the long arms of said levers, and an eccentric, G , connected with a lever, H , and acting as a stop 85 to the adjusting pieces and levers, while at the same time serving to actuate them both simultaneously for uniformly adjusting their respective rolls, substantially as and for the purpose described. 90

2. The combination of the middle roll in fixed bearings, the upper and lower rolls geared with the same, the vertical bell-crank levers $D' D^2$, pivoted at their angle, the short arms of the levers being provided with bearings, 95 within which the journals of the upper and lower rolls are respectively arranged, the vertical adjusting-pieces $F' F^2$, pivoted near one end to the long arms of the said levers and at their other end connected therewith by the 100 adjusting set-screws $I' I^2$, and the eccentric G , connected with a lever, H , and acting as a stop to the adjusting-pieces, while at the same time serving to actuate them simultaneously, substantially as described, for the purposes 105 set forth.

3. The vertical bell-crank levers $D' D^2$, pivoted at their angle and having their short arms provided with bearings, within which the journals of the upper and lower rolls are respectively arranged and supported in proper position, in combination with an eccentric, G , connected with a lever and acting as a stop to the long arms of the levers, and at the same time serving to actuate them simultaneously 110 for adjusting their respective rollers, and the spring-impelled bolts J , having at their inner ends the pins j , which are connected with the long arms of the bell-crank levers for keeping the latter in contact with the eccentric, all substantially as shown and described. 115

4. The combination, with the pivoted bent levers carrying the upper and lower rolls, $A' A^3$, of the adjusting-plates $F' F^2$, pivoted near one end to the long arms of said levers and 120 at their other end connected therewith by set-screws $I I'$, for adjusting the said rolls independent of each other, substantially as described. 125

5. The device for simultaneously adjusting 130

the two feed-openings of the hopper, consisting of the slides Q, screw-spindles R, and screwed bushes R', worked from spindle S by tooth-gear, substantially as described.

5 6. The device for effecting the independent accurate adjustment of each feed-opening, consisting of the slide Q, eccentric slotted plates Q', and subsidiary slides T, combined and operating substantially as herein described.

In testimony whereof I have signed my name to this specification, in the presence of two subscribing witnesses, this 2d day of August, 1879.

G. DAVERIO.
